COMBINATION SANITARY DEVICE

Elias C. Bishelany, Brooklyn, N. Y.

Application February 12, 1938, Serial No. 190,221

1 Claim. (Cl. 4—267)

This invention relates broadly to articles which may be classified as combination smokers' stands including spittoons, and has for its object the provision of such articles which may be conveniently used in homes, hotels, club rooms, hospitals, and other places. Such a stand made in conformity with the present invention is attractively ornamental, practically useful, and at the same time sanitary and efficient.

10 In the accompanying drawings as well as the following description, three different forms of devices showing practical applications of the invention, are set forth. These forms are presented as illustrative applications only, and it is not 15 desired that they should in any way be interpreted as the only possible forms of application of the invention, nor is it desired to limit the structure of any or all of these or other possible forms to the specific details of construction shown 20 or described, excepting as claimed.

Referring briefly to the accompanying drawings,

Figure 1 is a side elevational view of one form of the device.

25 Figure 2 is a front elevational view of the same. Figure 3 is a plan view of the same.

Figure 4 is a cross-sectional view taken on the line 4—4 of Figure 3.

30 Figure 5 is a cross-sectional view taken on the line 5—5 of Figure 3.

Figure 6 is a front elevational view of a modified form of the device.

Figure 7 is a plan view of the same.

35 Figure 8 is a cross-sectional view taken on the line 8—8 of Figure 7.

Figure 9 is a side elevational view of another modified form of the device.

Figure 10 is a plan view of the same.

40 Figure 11 is a perspective view of one form of a removable paper lining for the spittoon.

Referring in detail to the drawings, the numeral 10 represents an upright hollow housing rotatably mounted on a relatively heavy or weighted base 11 by means of an upright column or shaft

45 12. At the base of the housing 10 a plate 13 extends forward therefrom, and is provided with a central rib 14 on its upper surface. A box-like spittoon 15, having a groove in its underside corresponding with the rib 14, is slidably mounted 50 on the plate 13 with the rib 14 registering in the said groove. A cover 16 is hingedly secured to the box 15 and has a rigid upwardly-inclined tongue 17 extending therefrom through an opening in the housing 10 into the latter. The cover 16 is relatively heavy so that its weight will tend

to keep it normally closed, and along its lower periphery it is lined with rubber or the like to seal the box when closed. A spider 18 is mounted within the housing 10, through an opening in the center of which a rod 19 slidably extends. 5 The rod 19 extends upward through an opening in the top of the housing 10 and is provided with a suitable knob or handle 20. A rigid collar 21 is mounted on the rod 19 under the roof of the housing 10, and a coiled spring 22 surrounds 10 the rod between the collar and the spider 18, tending normally to hold the rod 19 in elevated position. A tapering nose 23 is secured to the lower end of the rod 19, and with the latter in elevated position its lower surface lies flush 15 against the upper surface of the tongue 17. Depression of the rod 19 causes lifting of the cover 16, and on release of the pressure on the rod the spring 22 again raises the rod and the cover 16 falls into closed position. If desired, any suitable means for accelerating the closing of the cover may be provided, and the latter is provided with a beveled rubber or felt under periphery 24 to soften the impact of closing. A pivoted handle 25 is provided for lifting and carrying the 20 device.

On one side of the housing 10 an opening 27 is provided and pivoted on the lower edge thereof is a door 26 adapted to be swung into horizontal position. An ash tray 28 is screw-threaded in the door 26, and a further hinged flap may be provided on the free end of the door, indented in the form of a pipe bowl or the like, so that when swung into horizontal position a pipe may be laid thereon. Diametrically opposite the opening 27 another opening 29 is provided in the housing 10, in which a vertically hinged barrel-shaped door 30 is mounted, within which matches or match boxes or cigarettes may be stood upright. In the back of the housing 10, between the above-mentioned openings, a third opening is provided, in which a door or the like 31 is either hinged or snapped, and the member 31 may be provided on its inside with means for holding cigarettes therein, in the manner of a cigaret case. 45

The box 15 is provided with pivoted hooks 32 adapted to engage pins 33 on the lower housing 10, to releasably retain the box on the base 13. In Figure 11 is shown a sanitary paper container adapted to be removably placed in the box 15. 50 This comprises a box-shaped body 34 open at the top. Intermediate opposite sides of the body 34, on the outer surface, a band 35 is attached at its upper and lower ends, leaving a space between the band and the body side between these extrem- 55

ties. A frame 36 having a cross-bar 37 near its lower end, is slidably mounted on the band 35 by passing the band upward between the lower end of the frame and the cross bar 37, that is, through the slot between these members. Normally, when the container is in the spittoon, the frames 36 are in pushed down position, and to remove the container the frames are lifted so that they first rise slidably on the body until the bars 37 reach the upper attached ends of the bands 35, after which further lifting of the frames results in lifting the container from the spittoon.

In the form shown in Figures 6, 7 and 8, which is more suitable for household use, and which may also be applied in modified form for use in railroad cars to be mounted between windows, the housing 38 has a set-back roof 39 on which a box 40, similar to the box 15, is similarly mounted. The cover of this box is also provided with a projection 43 which is engageable by the nose 42 on the vertically slideable rod 41. At its lower end the latter has a pedal 44 projecting through a slot in the housing. Operation of the opening and closing of the cover 45 of the box 40 by the pedal 44, is obvious. In the lower portion of the housing 38 a drawer 46 is mounted, into the top of which the tube 47, leading down from the ash receptacle 48, empties.

In the form shown in Figures 9 and 10, the housing 48 is tubular and the spittoon 49 is mounted in the base 50. The cover 51 is operated by the knob 52 in the same manner as the first-described form. Two complementary semi-circular ash trays 53 are set in the top opening of

the column 48, surrounding the stem of the knob 52, and they may be removed simply by lifting them and their contents emptied into said opening so that they will fall into the spittoon 49.

Obviously, the objects of this invention may be obtained in other and additional modifications in form and structure, without departing from the spirit and scope of the invention.

In any or all of the forms shown, any suitable means may be provided to keep the cover-lifting mechanism locked releasably when in depressed position, that is, when the cover is raised, to facilitate removal of the spittoon for cleaning.

I claim:

A device of the class described comprising an upright housing having a set-back step-like roof forming a right-angle recess thereon, a base having said housing mounted thereon, a vertical rod slidably mounted in said housing, a spittoon removably mounted on said roof in said recess, a cover hingedly attached to said spittoon and having a tongue projecting into said housing, a nose on said rod near the upper end thereof, resilient means for urging said rod upward, a collar on said rod adapted to engage the roof of the housing adjacent said recess to serve as an upper limit stop, said tongue normally lying against said nose, depression of said rod causing said nose to force said tongue downward and to lift said cover, said rod having an extension passing through said housing adapted to be acted upon to depress said rod.

ELIAS CH. BISHELANY.
